Patented Apr. 30, 1918.

UNITED STATES PATENT OFFICE.

JOHN T. McGRATH, OF BLOOMINGTON, ILLINOIS.

PNEUMATIC TOOL.

1,264,318.

Specification of Letters Patent. Patented Apr. 30, 1918.

Application filed April 26, 1917. Serial No. 164,609.

To all whom it may concern:

Be it known that I, JOHN T. McGRATH, a citizen of the United States, and a resident of Bloomington, in the county of McLean 5 and State of Illinois, have invented certain new and useful Improvements in Pneumatic Tools; and I do hereby declare that the following is a full, clear, and exact description thereof, reference being had to the accompanying drawings, and to the characters of reference marked thereon, which form a part of this specification.

This invention relates to improvements in pneumatic tool devices such as hammers, 15 chisels, riveting machines, and the like, and the invention refers more particularly to an improved valve mechanism by which the air or other motive agent is admitted to the cylinder and is exhausted therefrom.

20 The invention consists in the combination and arrangement of the parts shown in the drawings and described in the specification, and is pointed out in the appended claims.

Among the objects of the invention is to 25 provide a novel valve mechanism by which the inlet of air is controlled to and its exhausted discharged from the cylinder of the machine in such a way that the cylinder may be completely exhausted at the end of 30 the power stroke through relatively small exhaust ports, while at the same time the charge of air is retained in the cylinder a length of time sufficient to efficiently utilize 35 the effect of expansion thereof to operate the tool.

In the drawings:—

Figure 1 is an axial section of a pneumatic tool embodying my invention.

Figs. 2 and 3 are cross sections on lines 40 2—2 and 3—3 respectively, of Fig. 1.

Fig. 4 is a detail of the means for locking the tool shank to the socket member.

Fig. 5 shows a modified valve.

As shown in said drawings, 10 designates 45 the barrel of the tool which is internally bored to provide a cylinder 11 in which reciprocates a piston 12. Said piston is attached to or made integral with a hammer 14, composed of a hammer head and shank, 50 and the bore of the barrel is reduced beyond the diameter of the cylinder at 15 to such diameter that the hammer shank fits closely therein. The outer end of the barrel is

formed to provide a socket member 16 to receive the shank 17 of the cutting or riveting 55 tool 18. The opposite end of the barrel is partly closed by the end wall 19 of a hollow cap 21 that is threaded over the end of the barrel and said end wall is centrally apertured to provide a port 20. The outer 60 end of said cap is closed by a coupling 24 that fits within and is threaded to the cap and is flanged to extend over the end of the cap at 24'. The said cap incloses a pressure chamber 23 which is in communication with 65 a main air pipe 25 through a series of ports 22, and said pipe is provided with any usual or preferred type of operating valve 26.

The port 20 is controlled by a valve 28 that is provided with a valve stem 29 which 70 extends through said port 20 and into the cylinder; and the cylinder and hammer shank are centrally apertured to provide a guide passage to receive said stem, the stem having a close sliding fit in said passage. 75 That portion of the stem which enters said guide passage is hollow. Said valve stem is provided between the piston and the wall 19 of the closing cap with a shoulder 31 which is engaged by the piston, when the latter moves outwardly, in a manner to lift the valve 28 off of its seat. The valve stem is also provided inwardly beyond said shoulder with a plurality of exhaust ports 32 which are spaced both angularly about and longitudinally along the valve stem. In certain positions of the piston the ports are within the central guide passage of the piston and hammer shank and are therefore closed, and in other positions of the piston and shank the 90 ports 32 are uncovered so as to afford communication between the cylinder and the hollow valve stem. The inner end of the stem may be open to discharge air into the central guide passage of the piston and hammer shank and the body of the hammer 95 shank is provided with a series of radial, angularly spaced ports 33 which, when the hammer is at its full power stroke afford communication between said central guide 100 passage and an exhaust space 35 within the outer end of the barrel, which space communicates with the atmosphere through a series of radial ports 36.

The pressure chamber 23 in the cap 105 communicates with the cylinder 11 at a point

below the inner face of the piston 12 through a port 38 formed partly in the wall of the barrel radially exterior to the cylinder and communicating with the pressure chamber 5 through a port 39 in the cap 21.

As herein shown, and preferably made, the valve 28 is formed with a cylindric extension 28', which fits closely within a hollow cylindric flange 24², preferably circular, 10 which depends from the coupling 24 radially within the ports 22. This arrangement decreases the area of the valve subject to the full pressure of the pipe 25 and enables the valve to be lifted with less power. Furthermore, 15 said arrangement is advantageous, inasmuch as it constitutes a guide for the valve, longitudinally spaced from the engagement of the stem 29 with the passage in the piston, and avoids side pressure of said stem with the wall of said passage. A small vent passage 24³ is provided in the coupling, which prevents air locking of the valve in the event of leakage of air past the extension 28'.

25 The operation of the tool described is as follows:

When the operating valve 26 is opened and the cylinder and hammer occupy the position shown in Fig. 1, or any other position 30 between this and its full stroke, air under pressure is admitted to the cylinder through port 38 beneath the piston 12 and forces the same, together with the hammer, outwardly. Contact of the piston with the shoulder 31 35 of the valve stem, in the outward movement of the piston, acts through the valve stem to lift the valve 28 off of its seat and to open the port 20 so that the full air pressure of the chamber 23 is exerted on the outer face 40 of the piston. At this time the piston has passed over the exhaust ports 32 of the valve stem and the exhaust ports 33 of the hammer are within the restricted portion 15 of the barrel, so that the air entering the outer 45 end of the cylinder acts with its full force on the piston, and counter to the smaller pressure active against the smaller area of the inner face of the piston to move or thrust the hammer inwardly against the shank of 50 the tool. After the piston has traveled through somewhat more than half of its stroke the exhaust ports 32 are uncovered and the hammer is moved outwardly sufficient to uncover the exhaust ports 33. These 55 exhaust ports are made relatively small so that the air is gradually exhausted from the cylinder, but are made sufficiently numerous and spaced longitudinally of the valve stem so that when the piston has reached its full 60 stroke sufficient exhaust valve area is provided to fully exhaust the air. The construction described efficiently utilizes the expansive force of the air, and at the same time provides for a complete clearance of 65 the air from the cylinder before the piston is

again retracted under the pressure directed against the inner face of the piston through the port 38. The ports 36 are sufficiently large to permit free exhaust of the air from the exhaust chamber 35 after it passes 70 through the ports 33.

So far as the broader features of the exhaust valve mechanism are concerned, it will be understood that the same general effects may be secured by providing exhaust 75 ports, which function as do the exhaust ports 32, of other form and in other parts of the device in a position to be controlled by the reciprocating movement of the piston instead of placing the same in a hollow valve 80 stem as herein shown. For instance, I may employ two or more oblong ports 32', shown in Fig. 5 which are narrowed at their upper ends and widest at their lower ends.

The tool shank 17 is made of an external 85 diameter smaller than the internal diameter of the socket member 16 and is provided with spaced shoulders 40, 41, which latter fit closely in the bore of the socket. The tool is held in place by means of short stout 90 pins 42 which extend through radial openings in the socket member and enter the annular space between the reduced part of the shank and the bore of the socket and intermediate the shoulders 40 and 41 of the 95 shank. Said pins limit the outward movement of the tool when it is struck by the full force of the hammer and is not otherwise limited in its movement by its contact with the work.

As a means for holding the limiting pins 42 in place a locking sleeve 44 is provided, which may be made of light sheet metal, and of a diameter to slip closely over the external cylindric face of the socket member. 105 This sleeve need only be made of small gage, inasmuch as but little work is imposed on it to hold the pins in place. The sleeve may be locked in place by providing it with an L-shaped bayonet slot 45 which may coöperate with a short locking pin 46 that is seated in a notch in the socket piece. The shape of the slot 45 is such that when the sleeve is placed on the socket piece the slot will pass over the locking pin 46, and by a slight angular movement of the sleeve and thereafter forcing the sleeve outwardly the pin engages a locking notch 47 in one end of the L-shaped slot.

It is to be understood that the structural 120 details of the invention may be somewhat varied from those herein shown and described, and the invention is, therefore, not limited to the particular details, except as to the claims wherein they are specifically set forth, 125 or as imposed by the prior art.

I claim as my invention:

1. In a pneumatic tool, a barrel formed to provide a cylinder, a differentially faced piston reciprocable in said cylinder, with 130

- means to constantly admit air from a source under pressure to said cylinder at the smaller face of said piston and other means to controllably admit air from said source 5 to the larger face of said piston, including a valve actuated by movement of said piston, there being exhaust ports arranged longitudinally of the axis of said cylinder through which spent air is exhausted, with 10 means whereby said ports are progressively opened to release pressure against said larger face of the piston during the latter part of the power stroke of the piston.
2. In a pneumatic tool, a barrel formed 15 to provide a cylinder, a differentially faced piston reciprocable in said cylinder, with means at one end of the cylinder to constantly admit air from a source under pressure to said cylinder at the smaller face of 20 said piston, and other means controlled by the piston to controllably admit air from said source to the cylinder at the larger face of said piston, there being a series of exhaust ports spaced annularly around and 25 longitudinally along the axis of said cylinder through which spent air is exhausted, with means whereby said ports are progressively opened during the latter part of the power stroke of said piston.
3. In a pneumatic tool, a barrel formed to 30 provide a cylinder, a differentially faced piston and hammer reciprocable in said cylinder, with means to admit air from a source under pressure to said cylinder to the opposite faces of said piston, said piston and hammer being provided with a central guide 35 passage that communicates with the atmosphere through suitable ports, and a tubular member extending into said guide passage and provided along its length with elongated exhaust ports which are adapted 40 to be covered and uncovered in the travel of said piston.
4. In a pneumatic tool, a barrel formed 45 to provide a cylinder, a differentially faced piston and hammer reciprocable in said cylinder, with means to admit air from a source under pressure to said cylinder at the opposite faces of the piston, said piston and hammer being provided with a central guide 50 passage that communicates with the atmosphere through suitable ports, a tubular member extending into said guide passage and provided with elongated exhaust ports which 55 are adapted to be progressively covered and uncovered in the travel of the piston, the said hammer shank being of smaller diameter than the piston and fitting closely in a reduced portion of the barrel, ports extending 60 from the inner end of the guide passage and adapted to be closed by the wall of the barrel when the piston is traveling through the outer limits of its stroke, the barrel being provided with an exhaust chamber 65 with which said ports communicate at

the end of the power stroke of the piston and with ports leading from said exhaust chamber.

5. In a pneumatic tool, a barrel having a cylinder of unequal diameter in its length, 70 a piston reciprocable in the larger diameter of the cylinder, a hammer reciprocable in the smaller diameter of the cylinder and connected to the piston, a valve for controlling the flow of air to the cylinder against 75 the larger face of the piston, there being a passage to direct the air to the cylinder against the smaller face of the piston, and means whereby said valve is opened when the piston recedes from its power stroke, 80 there being exhaust ports disposed longitudinally of the axis of the piston and adapted to be progressively covered and uncovered by the piston in its travel.

6. A pneumatic tool comprising a barrel 85 having a cylinder of unequal diameter in its length, a piston reciprocable in the larger diameter of the cylinder, a hammer connected thereto and reciprocable in the smaller diameter of the cylinder, a valve for 90 controlling the flow of air to the cylinder against the larger face of the piston, with means to direct air under pressure to the cylinder against the smaller face of the piston, said piston and hammer being provided 95 with an axial guide passage, and a hollow stem connected to the valve and extending into and communicating with said passage and provided with a shoulder which is engaged by the piston to unseat the valve, and 100 provided also with longitudinally disposed exhaust ports adapted to be covered and uncovered by the piston in its travel.

7. A pneumatic tool comprising a barrel having a cylinder, a differentially faced piston reciprocable in the cylinder, a hammer reciprocable in the cylinder and connected to the piston, a valve for controlling the flow of air under pressure to the cylinder against the larger face of the piston, with means to 105 direct the air under pressure to the cylinder against the smaller face of said piston, said piston and hammer being provided with an axial guide passage, and a hollow stem connected to the valve and extending into said 110 passage, with means whereby the movement of the piston controls said valve, said stem being provided with longitudinally disposed exhaust ports which are adapted to be covered and uncovered by the piston in its 115 travel.

8. A pneumatic tool comprising a barrel having a cylinder, a differentially faced piston reciprocable in the cylinder, a hammer reciprocable in the cylinder and connected 125 to the piston, a valve for controlling the flow of air under pressure to the cylinder against the larger face of the piston, with means to direct the air under pressure to the cylinder against the smaller face of said 130

piston, said piston and hammer being provided with an axial guide passage, and a hollow stem connected to the valve and extending into said passage, with means whereby the movement of the piston controls said valve; said stem being provided with longitudinally disposed exhaust ports which are adapted to be covered and uncovered by the piston in its travel, said barrel being provided at its tool holding end with an exhaust chamber having exhaust ports, and the working end of the hammer being provided in its body with radial ports which afford communication between said guide passage and said exhaust chamber when the hammer is at the end of its power stroke.

9. A pneumatic tool comprising a barrel formed to provide a cylinder, a differentially faced piston and connected hammer reciprocable in the cylinder, a pressure chamber at one end of the barrel, there being a port affording communication between the pressure chamber and cylinder at the larger side of the piston, with a passage affording communication between the pressure chamber and said cylinder at the other face of the piston, and a valve controlling said port and provided with a hollow stem, said piston and hammer being provided with a guide opening to receive said stem, and the stem being provided with longitudinally disposed exhaust ports which are opened and closed by the piston, with means whereby spent air is exhausted from the hollow valve stem.

10. In a pneumatic tool device, a cylinder, a differentially faced piston therein, there being a port through which full fluid pressure is delivered to the larger face of said piston, with a controlling valve therefor, and a passage through which fluid is delivered at constant pressure to the smaller face of the piston, together with means to progressively release the exhaust from the cylinder toward the end of the power stroke of the piston and to afford full clearance exhaust opening at the end of said power stroke.

11. In a pneumatic tool device, a cylinder, a piston, a hammer operated thereby, there being a port through which full air pressure is delivered on said piston to operate the hammer, and a valve to control said port, provided with a hollow stem, the piston and hammer provided with a guide passage to receive said stem and having an exhaust opening, and the hollow stem being provided with longitudinally disposed exhaust ports which are alternately covered and uncovered by said piston.

12. In a pneumatic tool device, a cylinder, a piston, a hammer operated thereby, there being a port through which full air pressure is delivered on said piston to op-

erate the hammer, and a valve to control said port, provided with a hollow stem, the piston and hammer provided with a guide passage to receive said stem and having an exhaust opening, and the hollow stem being provided with longitudinally disposed exhaust ports which are alternately covered and uncovered by said piston, and means for delivering full air pressure through said port, while relieving the valve of said full pressure.

13. A pneumatic tool device comprising a cylinder of unequal diameter in its length, a piston reciprocating in the larger diameter of the cylinder and a connected hammer shank reciprocating in the smaller diameter of the cylinder, a hollow cap applied to the end of the cylinder and having a port and inclosing a pressure chamber, a valve to control said port and provided with an axial extension, a coupling threaded to said cap and provided with a flange to closely receive said extension, there being inlet ports in said coupling for directing air under pressure to the pressure chamber radially exterior to said extension, means to operate said valve and means to exhaust air from said cylinder.

14. A pneumatic tool device comprising a cylinder of unequal diameter in its length, a piston reciprocating in the larger diameter of the cylinder and a connected hammer shank reciprocating in the smaller diameter of the cylinder, a hollow cap applied to the end of the cylinder and having a port and inclosing a pressure chamber, a valve to control said port and provided with an axial extension, a coupling threaded to said cap and provided with a flange to closely receive said extension, there being inlet ports in said coupling for directing air under pressure to the pressure chamber radially exterior to said extension, said piston provided with an axial opening and the valve being provided with a hollow, ported stem to enter said opening.

15. A pneumatic tool device comprising a cylinder, a piston reciprocating therein, there being a port through which full fluid pressure is delivered to said cylinder against the piston to operate the same, a valve to control said port, with means whereby said valve is opened by movement of the piston, and means for delivering full fluid pressure through said port, while relieving the valve of said full fluid pressure.

16. A pneumatic tool device comprising a cylinder, a piston reciprocating therein, said cylinder being provided at one end with a pressure chamber, there being a port to connect said pressure chamber to said cylinder, a valve to control said port and a pressure pipe connected to said pressure chamber through passages which open into the pressure chamber radially at the sides of the cen- 130

ter of said valve, the wall of the pressure chamber being provided radially inside said passages with means which inclose a portion of the valve, whereby full fluid pressure 5 may be delivered through said port, while relieving said valve of said full fluid pressure.

17. A pneumatic tool device comprising a cylinder, a differentially faced piston reciprocating therein, said cylinder being provided at one end with a pressure chamber, there being a port to connect said pressure chamber to said cylinder at the larger face of the piston, a valve to control said port, 10 and a pressure pipe, connected to said pressure chamber through a passage which opens into the pressure chamber radially at the side of the center of said valve, the wall of the pressure chamber being provided with 15 means which inclose a portion of the valve, whereby full fluid pressure may be delivered through said port, while relieving said valve of said full fluid pressure, and there being also a constantly open passage connecting 20 said pressure chamber to the cylinder at the smaller face of the piston.

18. A pneumatic tool device comprising a cylinder, a piston reciprocating therein, there being a port through which full fluid 25 pressure is delivered to said cylinder against the piston to operate the same, a valve to

control said port, with means whereby said valve is opened by movement of the piston, said valve being provided with an axial extension and a flange on the wall of the pressure chamber surrounding said extension. 35

19. In a pneumatic tool device, a cylinder, a piston therein, and a valve member provided at one end with a valve piece and with an axial extension and reciprocable in the 40 axis of the piston, said valve member being provided on the side thereof remote from said extension with an axial stem and the stem being provided with exhaust ports disposed longitudinally of the stem. 45

20. In a pneumatic tool device, a cylinder, a hollow piston, and a valve member provided with a valve face piece and with a hollow stem to enter said hollow piston, said stem provided with exhaust ports disposed 50 longitudinally of said stem, and with a shoulder adapted for engagement by a moving part of said piston.

In witness whereof I claim the foregoing as my invention, I hereunto append my signature in the presence of two witnesses at Bloomington, Illinois, this 13th day of April, 1917. 55
